UNITED STATES PATENT OFFICE.

CHARLES F. DAMM, OF BUFFALO, NEW YORK.

STREET-CAR.

1,183,349.

Specification of Letters Patent.

Patented May 16, 1916.

Application filed April 26, 1915. Serial No. 23,829.

To all whom it may concern:

Be it known that I, CHARLES F. DAMM, a citizen of the United States, residing at Buffalo, in the county of Erie and State of 5 New York, have invented new and useful Improvements in Street-Cars, of which the following is a specification.

This invention relates to a passenger street car and more particularly to cars of 10 that type which require passengers to pay their fares upon entering the car and which are intended to stop at the near side of street crossings.

In cars of this character as heretofore 15 constructed comparatively little standing room is provided for passengers boarding the car between the entrance door and the conductor's station, so that the progress of a car is often delayed by reason of a conductor being unable to collect the fares, make change, issue transfers, &c., sufficiently 20 rapid to keep pace with the incoming passengers, which necessitates holding up the car until a sufficient number of passengers 25 have passed the conductor to permit all of the waiting persons desiring transportation to at least board the car.

Another disadvantage in the cars heretofore 30 in use is the congestion which occurs adjacent to the exit at the end of the same which renders it not only inconvenient for 35 passengers remote from the exit to leave the car but also materially slowing up the traffic.

Furthermore, the cars heretofore known 35 resulted in a pronounced conflict between incoming and outgoing passengers and also produced interference between passengers waiting at the entrance of the car to get on and passengers wishing to leave the car and 40 connect with another car either ahead or on a crossing street.

It is the object of my invention to provide 45 a passenger street car in which the objectionable features above enumerated are eliminated.

In the accompanying drawings: Figure 1 is a sectional plan view of a street car embodying one form of my invention. Fig. 2 is a similar view showing a slight modification 50 of my improvements.

Similar characters of reference indicate corresponding parts in both figures.

The passenger street car shown in Fig. 1 is assumed to be moving in the direction of

the arrow 1 for convenience in determining 55 the front and rear ends thereof. As there shown the car comprises a passenger's compartment 2 which is provided with two longitudinal side walls 3, 4 and a rear transverse wall 5 connecting the rear ends of the 60 side walls. About midway of the length of the car the right hand wall 4 is provided with an auxiliary or supplemental doorway having a door 6 which, if desired, may be used as an exit to supplement the main exit 65 at the front of the car in case a large number of passengers are being transported and the same may also be used as an emergency exit in case the front exit becomes blocked from any cause. 70

7 represents a short row of seats arranged adjacent to the right longitudinal wall of the compartment between the central door 6 and the rear end of the compartment, and 8 a long row of seats extending from the 75 front end to the rear end of the compartment along the left longitudinal wall 3.

9 represents a longitudinal partition arranged in the front part of the compartment and extending from the front end of the 80 same rearwardly to a place about midway between the front and rear ends of the compartment and terminating short of the central side door 6. This partition is preferably constructed in the form of a hand rail 85 so that passengers can steady themselves by taking hold of the same while standing both when entering or leaving the car through the front end of the same. As shown in the drawings this partition is arranged on one 90 side of the longitudinal center line of the car so as to form an incoming aisle 10 between the right hand side of this partition and the adjacent front part of the right hand longitudinal wall of the compartment 95 which is vacant or unprovided with seats, and also an outgoing aisle 11 between the left hand side of the partition and the front seats of the row arranged adjacent to the front part of the left hand longitudinal 100 wall 3.

12 represents the vestibule which is arranged at the front end of the car and provided with a rear entrance passageway 13 which leads to the front end of the incoming aisle, and a front exit passageway 14 which leads from the front end of the outgoing aisle, both of said passageways having 105

their doors 16, 17, respectively opening laterally from the vestibule to the ground or street on the same side of the car on which the auxiliary door and entrance aisle are arranged.

15 represents the conductor's station which is arranged in the compartment adjacent to the inner end of the partition and preferably between the auxiliary door and 10 the partition so that the movement of the passengers from the incoming aisle to the remaining space within the car and the exit of the passengers through the auxiliary door may both be under the control of the 15 conductor.

Persons desiring transportation enter the car through the entrance passageway of the vestibule and then pass rearwardly through the incoming aisle to the conductor in the 20 center of the car where the fare is paid before the passenger is permitted to enter the rear part of the car or the front part thereof or left of the partition where the seats are located. Inasmuch as the incoming 25 aisle is comparatively long a much larger number of passengers can be taken aboard the car and their fares collected in transit by the conductor than has been possible heretofore, thereby enabling the car to be 30 started promptly and reducing the delays incident to stopping cars an undue length of time when taking on a crowd of persons greatly in excess of the accommodation space between the conductor's station and 35 the entrance door.

As the passengers pass the conductor into the seating space of the car the same are likely to distribute themselves more uniformly over the entire compartment on account of the conductor being in the center 40 of the car and some passengers will go toward the rear and some toward the front of the car instead of an undue number of passengers remaining adjacent to the exit 45 at the front of the car as is commonly the case in "near side pay-as-you-enter cars" and thereby interfering with the free egress of persons desiring to leave the car. By thus getting the passengers first into the 50 center of the car and then distributing the same substantially even around the car space all crowding or jamming of passengers is avoided, more passengers can be accommodated comfortably and it is also possible for passengers to alight in much less time.

Furthermore, the partition divides the passengers into two distinct streams, one coming in and the other going out, whereby 55 conflict between the incoming and outgoing passengers is avoided and the transporta- of the same is facilitated. When a car is crowded with passengers it is desirable when letting off passengers to open both the 60 door of the front exit passageway of the

vestibule under the control of the motorman and also the side exit door in the center of the car under the control of the conductor, but if only a moderate number of passengers are in the car it is preferable to open 70 only the front exit door on account of the greater safety of this practice because the motorman can clearly observe when the passenger has left the car. By constructing the partition in the form of a hand rail the 75 passengers adjacent thereto can hold themselves thereon and avoid accidents.

In the operation of the car the motorman will be instructed to permit persons leaving the car through the entrance door 80 so that normally all persons are compelled to pass the conductor and pay the fare before being able to leave the car.

By placing the vestibule entrance in rear of the vestibule exit passengers alighting 85 from a car have a clear space ahead and can quickly transfer to another car instead of being delayed as frequently is the case in cars having the entrance door arranged in front of the exit door of the front vestibule 90 because such an arrangement requires passengers leaving a car to either walk around a crowd of passengers about to board a car or force a way through the same in order to make connection with another car ahead or 95 one running on a cross street.

Inasmuch as the passengers in this construction of car are under full control of the conductor the collection of all the fares is 100 insured.

If desired, the central side exit door of the passengers' compartment may be omitted, as shown in Fig. 2, in which case the seating capacity of the car may be increased accordingly.

This improved construction of car not only facilitates handling heavy loads of passengers with safety but also enables a larger number of passengers to be accommodated for a given area without liability 110 of missing any fares.

I claim as my invention:

1. A street car comprising a passenger's compartment, a partition extending lengthwise from one end of said compartment 115 toward that part thereof about midway between its opposite ends and forming longitudinal incoming and outgoing aisles in said compartment on opposite sides of said partition and an independent entrance and 120 exit arranged on the same side and end of the car and connecting respectively with said incoming and outgoing aisles.

2. A street car comprising a passenger's compartment, a partition extending lengthwise from one end of said compartment 125 toward that part thereof about midway between its opposite ends and forming longitudinal incoming and outgoing aisles in said compartment on opposite sides of said 130

- partition, and a vestibule having an entrance passage leading to one of said aisles and an exit passageway leading from the other aisle, said entrance passage and exit 5 passageway being independent of each other and arranged on the same side and end of the car. 3. A street car comprising a passenger's compartment, a partition extending lengthwise from one end of said compartment toward that part thereof about midway between its opposite ends and forming longitudinal incoming and outgoing aisles in said compartment on opposite sides of said 10 partition, independent entrance and exit passages arranged on the same side and end of the car and connecting with said incoming and outgoing aisles, respectively, and a conductor's station arranged in the compartment adjacent to the inner end of said 15 partition.
4. A street car comprising a passenger's compartment, a partition extending lengthwise from one end of said compartment toward that part thereof about midway between its opposite ends and forming longitudinal incoming and outgoing aisles in said compartment on opposite sides of said partition, a vestibule having an entrance passage 20 leading to one of said aisles and an exit passageway leading from the other aisle, and a conductor's station arranged in the compartment adjacent to the inner end of said partition, said entrance passage and exit 25 passageway being independent of each other and arranged on the same side and end of the car.
5. A street car comprising a passenger's compartment, a longitudinal row of seats 40 arranged in the space adjacent to one of the longitudinal walls of the compartment while the space adjacent to the opposite wall of the compartment is seat-less, and a partition extending lengthwise of the compartment from one end thereof to that part about 45 midway of its length and forming an incoming aisle between the partition and said seat-less wall of the compartment and an outgoing aisle between the partition and said row next to the opposite wall of the compartment. 50
6. A street car comprising a passenger's compartment, a longitudinal row of seats arranged in the space adjacent to one of the 55 longitudinal walls of the compartment while the space adjacent to the opposite wall of the compartment is seat-less, a partition extending lengthwise of the compartment from one end thereof to that part about 60 midway of its length and forming an incoming aisle between the partition and said seat-less wall of the compartment and an outgoing aisle between the partition and said row next to the opposite wall of the compartment, and a vestibule having an entrance 65
- passageway leading to said incoming aisle and an exit passageway leading from said outgoing aisle. 7. A street car comprising a passenger's compartment, a longitudinal row of seats 70 arranged in the space adjacent to one of the longitudinal walls of the compartment while the space adjacent to the opposite wall of the compartment is seat-less, a partition extending lengthwise of the compartment from one end thereof to that part about 75 midway of its length and forming an incoming aisle between the partition and said seat-less wall of the compartment and an outgoing aisle between the partition and said row next to the opposite wall of the compartment, and a vestibule having a rear entrance 80 passage and a front exit passageway which open laterally to the street on the same side of the compartment as said seat-less longitudinal wall, said entrance passageway leading to said incoming aisle and said exit passageway leading from said outgoing aisle. 85
8. A street car comprising a passenger's compartment, a longitudinal row of seats 90 arranged in the space adjacent to one of the longitudinal walls of the compartment while the space adjacent to the opposite wall of the compartment is seat-less, a partition extending lengthwise of the compartment from one end thereof to that part about 95 midway of its length and forming an incoming aisle between the partition and said seat-less wall of the compartment and an outgoing aisle between the partition and said row next to the opposite wall of the compartment, a vestibule having a rear entrance passage and a front exit passageway which open laterally to the street on the same side of the compartment as said seat-less longitudinal wall, 100 said entrance passageway leading to said incoming aisle and said exit passageway leading from said outgoing aisle, and a conductor's station arranged adjacent to the inner end of said partition. 105
9. A street car comprising a passenger's compartment, a longitudinal row of seats arranged in the space adjacent to one of the longitudinal walls of the compartment while the space adjacent to the opposite wall of the 110 compartment is seat-less, a partition extending lengthwise of the compartment from one end thereof to that part about midway of its length and forming an incoming aisle between the partition and said seat-less wall of the compartment and an outgoing aisle 115 between the partition and said row next to the opposite wall of the compartment, a vestibule having a rear entrance passage and a front exit passageway which open laterally to the street on the same side of the compartment as said seat-less longitudinal wall, 120 said entrance passageway leading to said incoming aisle and said exit passageway leading from said outgoing aisle, and an 125

auxiliary door arranged in the central part of that wall of the compartment next to said incoming aisle.

10. A street car comprising a passenger's compartment, a longitudinal row of seats arranged in the space adjacent to one of the longitudinal walls of the compartment while the space adjacent to the opposite wall of the compartment is seat-less, a partition extending lengthwise of the compartment from one end thereof to that part about midway of its length and forming an incoming aisle between the partition and said seat-less wall of the compartment and an outgoing aisle between the partition and said row of seats

next to the opposite wall of the compartment, a vestibule having a rear entrance passage and a front exit passageway which open laterally to the street on the same side of the compartment as said seat-less longitudinal wall, said entrance passageway leading to said incoming aisle and said exit passageway leading from said outgoing aisle, an auxiliary door arranged in the central part of that wall of the compartment next to said incoming aisle, and a conductor's station arranged within the compartment between said auxiliary door and the inner end of said partition. 20 25
